Joshua Brooks of Newton Mass.
Letters Patent No. 2313 - Dated May 15, 1866
Design for Card Holder.

The schedule referred to in these Letters Patent and making part of the same.

to all whom it may concern:

Be it known that I, Joshua Brooks, of Newton, in the County of Middlesex, and State of Massachusetts, have originated and designed a new form for Card Holders, of which the following is full and exact description, reference being had to the accompanying drawings, making part of this specification.

Figure 1 is a front elevation of the card holder.

The rectangular frame A has a narrow inner border C, and the included space is divided by parallel bars C and H, into squares or compartments. B. At or near the central portion of the frame there is a small frame (suitable for a mirror or picture) and at each of the intersections of the bars C and the bars H, there are knobs or projections E.

Figure 2 is a section on the line y - y figure 1.

That I claim as my invention and desire to secure by Letters Patent. The design for a Card Holder, as hereinafter set forth:
